FIG. 1 is a perspective view of one embodiment of a light fixture embodying our design, with the lamp housing tilted downwardly with respect to the ballast housing and mast fitter thereof, and as seen from the front, one side and bottom thereof;

FIG. 2 is a perspective view of such one embodiment, with the lamp housing tilted upwardly with respect to the ballast housing and mast fitter, and as seen from the front, other side and top thereof;

FIG. 3 is a side view of such one embodiment;

FIG. 4 is a rear view of such one embodiment;

FIG. 5 is a perspective view of a second embodiment of a light fixture embodying our design, with the lamp housing tilted downwardly with respect to the ballast housing and mast fitter thereof, and as seen from the front, one side and bottom thereof;

FIG. 6 is a perspective view of such second embodiment, with the lamp housing tilted upwardly with respect to the ballast housing and mast fitter, and as seen from the front, other side and top thereof;

FIG. 7 is a side view of such second embodiment; and

FIG. 8 is a rear view of such second embodiment.

The smooth surface on the front of the lamp housing of each embodiment is a window. The upper end of the mast shown in broken lines in each of the figures is for illustrative purposes only and forms no part of the claimed design.

We claim:

The ornamental design for a light fixture, substantially as shown and described.
